WASHER AND METHOD OF MAKING

Leonard A. Young, Detroit, Mich.

Application August 12, 1937, Serial No. 158,749

5 Claims. (Cl. 10—74)

This invention relates to improvements in washers and method of making.

The main objects of this invention are:

First, to provide an improved method of making washers which enables the manufacture of washers without waste.

Second, to provide an improved method of manufacturing washers by means of which a superior product may be economically produced.

10 Third, to provide a method of making washers which enables the making of washers from straight round stock such as wire stock, the resulting product being in effect endless.

15 Fourth, to provide a washer formed of straight stock which has all the advantages of a washer punched from flat stock.

Objects relating to details and economies of the invention will appear from the description to follow. The invention is defined in the claims.

20 A preferred embodiment of the invention is illustrated in the accompanying drawing, in which:

Fig. 1 is a conventionalized side view of a machine for performing initial steps of my method of manufacturing washers.

Fig. 2 is a plan view of a ring illustrating one of the steps of my method.

Fig. 3 is an enlarged elevation of a ring illustrating an intermediate step in the practice of 30 my method.

Fig. 4 is a fragmentary view partially sectioned illustrating the final step of my method.

Fig. 5 is a perspective view of my improved washer and an enlargement thereof, the joint 35 being indicated by dotted lines.

Fig. 6 is an enlarged detail section through the joint.

Fig. 7 is a blank from which my improved washer is formed.

40 I have made no attempt in the drawing to show the parts in their accurate proportions, and I have only shown the forming parts of the machine, that is, I have not attempted to illustrate actuating and synchronizing connections therefor.

45 In the accompanying drawing 1 represents a piece of wire or light rod stock which is suitably fed, preferably by coacting friction rollers 2. The stock may be drawn from a bale of wire of proper gauge through a straightening mechanism as is 50 well known in wire working machines. The stock is advanced by the feed means against a stop 3 disposed in opposed relation to the feed means and is fed across a suitable forming mandrel 4. The stock is advanced across the shear block 5 positioned to coact with the reciprocating shear

member 6 which is carried by the forming member 7 having a segmental forming recess 8 therein. The shear members 5 and 6 are conformed to form a V-shaped recess 9 in one end of the blank and a corresponding tongue 10 in the other end. 5 The shapes of these tongues and recesses may be very considerably varied but this V shape is found to be highly satisfactory and greatly simplifies the manufacturing steps, and the cutters for these shapes are easily maintained.

10 It will be noted that the severing of the blank 11 in the embodiment illustrated is accompanied by a partial forming operation which is completed on the full stroke of the member 7 to form the stock into a U-shape around the mandrel 4 15 as shown by dotted lines at 12.

The opposed forming jaws or members 13 are then actuated simultaneously to complete the forming of the stock into a complete ring 14 with the tongue and slot recess nested or in interlocking engagement. The V-shaped tongue and recess are of advantage in that they effectively coact to guide the ends of the ring into joint forming position and simple forming mechanism is all that is required.

20 After the ring 14 has been formed it is then flattened. This is preferably accomplished while still upon the mandrel 4 which is surrounded by a die member 15, the die member serving as an anvil or support for the work while the coacting die member 16 having a recess 17 therein is actuated. The forming member 4 serves as a gauge member for the internal diameter of the washer while the recess 17 serves as a gauge for the external diameter. It will be understood that these 30 die members are actuated at predetermined distances according to the washer to be formed, and this is gauged or determined by the diameter of the stock employed. It will be noted in Figs. 2 and 4 that the outer diameter of recess 17 is greater than the outer diameter of ring 14, whereas the diameter of mandrel 4 and the internal diameter of the ring are necessarily the same. This results in flowing of the metal of the ring radially outwardly. It is a much more simple matter to 40 cause the metal of an annular member such as ring 14 to flow outwardly than it is to force the same radially inwardly, due to the arching effect inherent in the ring under such a condition. Accordingly, it will be seen that by employing mandrel 4 as a forming member for the die operation I not only simplify the apparatus employed, but also work the metal in the most practical manner.

45 The actuation of the forming dies 15, 16 flattens the ring 14 into its washer-like form 19 and causes 50

55

the metal to flow into shape and to form an effective interlocked seam as indicated at 18, Fig. 6.

It is found that with metals such as copper, aluminum and certain steel there is a cold weld interlocking or flowing of the metal at the joint. The resulting joint is such that an endless washer results.

If a stronger joint is desired than results from the operations described the ring may be electrically welded at the joint before the forming operation, but this is not deemed necessary in producing washers for ordinary purposes or uses. In fact, the joint is almost entirely obliterated by the flattening operation when the stock is of the character of metals indicated.

It will be apparent that there is no waste by this method such as occurs when the washers are punched from flat stock as is very common practice, and thus a great saving in material is effected. This saving of material is highly important in the higher priced metals such as copper, brass and aluminum, but it is also an important factor in forming washers of ferrous metals.

A further advantage is that there is no machining or finishing required and no loss resulting therefrom. Should the dies be such that some flash results from the die pressing operation, this can be removed by a tumbling operation, but there apparently is no necessity for using dies that will require even the tumbling.

While I have illustrated perfectly round washers or washers of symmetrical shape, it will be understood that the shape of the washers may be greatly varied to meet particular conditions.

I have illustrated the steps of my improved method and the product mainly in conventional form. I have not attempted to illustrate or describe various details or apparatus which might be used as it is believed that this disclosure will enable those skilled in the art to practice my invention in different practical uses.

Having thus described my invention what I claim as new and desire to secure by Letters Patent is:

1. The method of making washers which comprises the steps of forming a split ring with end parts in interlapping relation, and subjecting the formed ring to a pressing die which flattens the same into a flat washer while increasing the diameter of the ring and determines the exterior and the interior dimensions of the finished washer and causes the metal to effect a cold weld engagement at the joint.

2. The method of making washers which comprises the steps of forming wire stock into a ring with joint parts in co-engaging relation, and die pressing the ring to form a flat washer, while permitting the metal of the ring to flow radially outward to increase the outer diameter of said ring.

3. As an article of manufacture, a flat washer resulting from the steps of forming a blank with a recess in one end and a coacting tongue in the other of wire stock, forming into a ring, and pressing the ring in a die to dimensions and causing the metal to flow into intimate abutting interlocked relation at the joint, said washer having a larger diameter than said ring.

4. As an article of manufacture, a flat washer resulting from the steps of forming a ring with end parts in co-engaging relation, and die forming the ring to flatten the same and cause the metal at the co-engaging ends to flow into intimate interlocked relation, the washer having a greater diameter than the ring.

5. As an article of manufacture, a flat washer resulting from the steps of forming wire stock into a ring with end parts in co-engaging relation, and die pressing the ring to form a flat washer, said washer having a greater outer diameter than the ring.
